MACHINE FOR PRINTING FACSIMILES OR
THE LIKE

Eugene A. Ford, Scarsdale, N. Y., assignor to International Business Machines Corporation, New York, N. Y., a corporation of New York

Application July 11, 1939, Serial No. 283,837

6 Claims. (Cl. 101—235)

This invention relates to machines for printing facsimiles such as signatures on checks or the like and has for its general object the provision of a printing machine having improved printing mechanism controlled by record controlled means and from a predetermined set-up device. Included with said printing mechanism is a novel removable inking roll therefor, and provision is made for the removal of the roll 5 from its inking position when the machine is idle. A special container is provided for receiving this roll to prevent drying of the ink regardless of the length of time the machine is in disuse. 10 More specifically, it is the object of the instant invention to provide improved printing means normally held inoperative but rendered operative to effect printing on predetermined portions of records upon passage of said records 15 into the printing position, that is, until a predetermined number of records have received imprints thereon, at which time a pre-settable device renders the record controlled means ineffective to operate the printing means. 20 Other objects of the invention will be pointed out in the following description and claims and illustrated in the accompanying drawings, which disclose, by way of example, the principle of the invention and the best mode, which 25 has been contemplated, of applying that principle.

In the drawings:

Fig. 1 is a front elevation view of the machine partly cut away to show the set-up control mechanism.

Fig. 2 is a sectional view taken at 2—2 of Fig. 1.

Fig. 3 is a sectional view taken at 3—3 of Fig. 2.

Fig. 4 is an enlarged detail view in section of the printing mechanism and the operating means therefor.

Figs. 5, 6 and 7 are wiring diagrams of the circuits of the machine under different operating conditions.

Feed mechanism

It is contemplated to use checks in the form of record cards C which are placed in a magazine 10 from which they are fed one by one by a card picker 11 into engagement with successive pairs of feed rolls 12, 13, and 14 which carry the cards eventually to receiving pocket 15, the cards being deflected downwardly into the pocket 55 by deflector spring 16.

The drive mechanism for the feed rolls includes a suitable drive motor 20, pulley 20a, belt 19, pulley 18, shaft 17, through suitable gear connections 17a to the feed rolls 12, 13 and 14. Thus, the feed rolls are in continuous rotation as long as the motor is operated. Suitable switching means may be provided for starting and stopping the motor as will be explained later in connection with the wiring diagrams. 5

Card lever mechanism

At the first of the three card feed roll positions is a U-shaped card lever CL (Figs. 3, 4) which is pivoted on a stud 22a fastened to a supporting bracket 22. The card lever is normally actuated by a pin 21 which is moving continuously in a circular path by virtue of the constant rotation of the feed roll 12 to which the pin is fixed. The actuation of the card lever consists of rocking it counterclockwise about the pivot stud from a position within the card line as shown in Fig. 4 to a position wherein the upper arm of the card lever lies just below the card line and substantially parallel therewith. The card lever is restored to its normal position 20 by the lower strap of a pair of contact springs 25 CLC which, incidentally, are located so as to be closed by the card lever when the latter is in its operated position. 25

At such times as cards are being fed from the magazine 10, card lever CL is held in its retracted position by the passage of the cards, thereby causing the end of the lower arm of the card lever to be positioned below rather than in abutting engagement with pin 23 on a cam follower arm 24. This permits free movement of pin 23 and hence arm 24 to the right as viewed in Fig. 4. Arm 24 is pivotally mounted at its upper end on a bracket 22, and as the arm is permitted to swing to the right a roller 25a 40 carried thereby operatively engages the periphery of a cam 25 fixed to the feed roll shaft 12. The follower arm 24 also carries a roller 26 which cooperates with the rounded end of a latching lever 27 of the printing mechanism in a manner to be described presently. When arm 24 moves to the right, roller 26 is removed from the path of lever 27 which therefore remains in its normally latched position on pin 28. Under these conditions, printing plate P is held in the operative printing position. 45

When cards stop feeding, the card lever CL is urged upwardly to its normal position under the bias of the lower strap of contacts CLC. During this movement, the lower arm of the card 55

lever is positioned in the path of pin 23 once more to prevent the arm 24 from becoming actively engaged with cam 25. With the card lever in the normal position, roller 26 engages the 5 rounded end of latching lever 27 once during each revolution of the printing mechanism so as to trip the lever free of the pin 28 and permit the printing plate P to retract toward the feed roll shaft 13 and hence out of printing position. 10

Printing mechanism

The printing mechanism is located at the second feed roll station and comprises a U-section piece 30 pivoted on a shaft 29 so as to straddle the lower feed roll shaft 13. A coil spring 29a carried by shaft 29 connects the member 30 for counterclockwise rotation with the feed roll. Integral with the U-section piece 30 is the printing plate P and pivotally mounted thereon is the latching lever 27 mentioned above. The entire mechanism, including latch pin 28, rotates with the feed roll. As long as lever 27 remains latched on pin 28, the printing plate P is maintained in printing position so as to cooperate alternately with an inking roll 32 and a platen 59 during the course of rotation of the plate, ink being taken by the plate from the roll 32 to effect printing on the under side of the cards as they pass the platen 59. However, in the event that the lever 27 is tripped, the printing plate will retract under the impetus of spring 29a so as to no longer engage with the platen. Plate P, once in its retracted position, is restored to the printing position each revolution by cam plate 30a on member 30. This is effected by contact of cam plate 30a with a roller 31 carried by bracket 22 which causes the U-section piece 30 to be cammed in a direction which opposes the bias of spring 29a so as to permit the latching end of lever 27 to fall behind the latch pin 28. The camming action imparted to the member 30 causes the printing plate P to be moved outwardly from feed roll shaft 13, and the printing plate to be maintained in an outward position as long as lever 27 remains latched. 40

It should be kept in mind that the card lever and associated mechanism control the position of the printing plate in accordance with whether or not cards are feeding and that the printing plate is restored during each revolution in which it has been retracted so that it is prepared for printing during the next revolution should a card have been fed by the card lever by that time. 55

Inking mechanism

The printing plate, as previously mentioned, contacts with a felt inking roll 32 (Fig. 2) during every revolution which causes a proper supply of ink to be provided on the inking plate for printing its impression on the card. Ink is supplied from a pump reservoir R (Fig. 1) by a pump (not shown) which regulates the quantity of flow. From the pump reservoir the ink is carried by a tube 33 which extends within the felt roll 32 and is provided with small holes 34 at the position of the roll. Tube 33 being stationary and felt roll 32 being adapted for rotation about the tube, the ink is distributed outwardly to the felt. The mounting for the felt includes a tubing 35 with holes 36 therein to permit free flow of the ink from inside to outside. 70

When the machine is not in use, the felt roll 75 is generally removed to prevent drying of the

ink. To accomplish this it is necessary simply to pull the knob 37 to the left, as viewed in Fig. 2. The tubing 35, felt 32 and locking springs 38 are all attached to the knob 37 and consequently are removed as a unit. The roll is then 5 slipped into container 39 on a centralizing rod 40 which positions the roll properly within the tube. Also, tubing 35 has a rubber washer 41 which, when placed in the container, seals the opening to prevent circulation of the air from 10 the outside to the inside of the container.

The inking roll assembly, when in inking position, is mounted on a tubing 42 which has a bearing 43 carried by an arm 44 (Fig. 4) biased upwardly toward the printing mechanism by 15 means of a spring 44a. An adjustable stop 44b is provided to limit the upward travel of arm 44 so that the ink roll 32 may be adjusted to the desired pressure in relation to the printing plate P. The tubing 42 is driven by a frictional wheel 20 54 which is of flexible construction to compensate for this pressure adjustment of the tubing. Wheel 54 engages an enlarged diameter portion of feed roll 55 which has a gear 56 fastened thereto and operable from the rotating 25 drive of shaft 17.

Predetermined counter

An additional function of cam arm 24 (Fig. 4) is to operate a predetermined counter through a 30 link 53 connected to the lower end of arm 24 and extending to the counter, generally designated B (Fig. 1) to form a loose connection with an arm 60 extending outwardly from a pivot 61 of the predetermined counter. In the normal operation of the counter, the link 53 transmits the required movement to arm 60 to step the counter step by step toward the home position which is shown in Fig. 1. When in this position, it will be noted that an operating lever 63 pivoted at 40 64 is seated in the depressed portion of the periphery of circular cam plate 62. A pair of contacts 65, which are biased toward the closed position, are held open by lever 63 at this time. Under normal operating conditions, however, lever 63 is out of the depressed portion of cam plate 62 and consequently contacts 65 are permitted to close. The purpose of these contacts is to prevent operation of the machine unless the counter is pre-set, as will become evident later 50 in the explanation of the circuit diagrams. 45

The diagrammatic disclosure of the counter in Fig. 1 is deemed sufficient in view of the fact that counters of this type are of common knowledge in the art. The object of the counter is to permit the machine to be pre-set for the feeding of a specified number of cards and, at such times as that specified number has passed through the machine, the counter will lock link 53 against movement and thus prevent cam arm 24 from 60 following cam 25. In this manner, a condition is created which is the same as if the card lever L were allowed to move out of its retracted position. Thus, it is seen that printing is rendered ineffective either when no cards are feeding or when a specified number of cards has been fed through the machine in accordance with the predetermined setup of the counter. 65

In order to protect the predetermined counter against tampering by one not in authority, the 70 machine is provided with three key cylinder locks L1, L2, and L3, with special keys for operating them individually. Each key cylinder when in a locked position will in itself prevent access to the predetermined counter by keeping door 75

45 in a locked position. In order to set the counter, this door must be opened by one of the special keys. Cylinders L2 and L3 are provided with cam operating portions 56 and 60 respectively 5 which, when in locked position, engage arm 57 pivotally carried by shaft 58, thereby preventing turning of the shaft on which latch 59 is attached, so that the latch point of latch 59 remains over the end of door 45 and secures it 10 against opening. A pair of contacts 51a, normally open but biased toward the closed position, are controlled by the position of arm 57.

Key cylinder L1 has an extra function, i. e., that of lifting pawl 51 out of engagement with ratchet 52 so as to unlock the drive, the only purpose of the ratchet wheel being to prevent the machine from being run by hand when key cylinder L1 is locked. Ratchet 52 has driving connection with shaft 17 so that turning of this 20 shaft manually may not occur while pawl 51 is seated in a tooth of the ratchet. When the pawl is moved up out of the ratchet it closes a pair of contacts 49 which are connected in the start circuit of the machine as will be explained presently.

Circuits

The circuits of the machine are simple as is evidenced by the disclosure in Figs. 5, 6 and 7. 30 Each of these figures shows a diagram of the circuits under different assumed conditions, and each will now be considered in turn.

Referring to Fig. 5, it is noted that key cylinder L1 has been operated to close contacts 49, that cam plate 62 has actuated lever 63 to close counter contacts 65 denoting a pre-setting of the counter, and that key cylinders L2, L3 remain locked so as to hold contacts 51a open. Depression of start key closes contacts ST to complete a circuit from line 71, motor relay magnets MR, contacts 65, card control relay CR start key contacts ST, contacts 49, to line 72. The purpose of motor relay magnets MR is to operate a pair of contacts MR-1 and MR-2 to complete a circuit to the motor 20 through these 40 contacts and contacts 49. The purpose of card control relay CR is to prevent starting the machine by any other means than depressing the start key. Once the card control relay is energized it closes a pair of contacts CR-1 to complete a circuit in conjunction with the card lever contacts CLc for maintaining the machine in operation until a predetermined number of cards have been fed through the machine according to the counter set-up. The circuit is traceable from line 71 magnets MR, contacts 65, card control relay CR, contacts CR-1 and card lever contacts CLc both now closed, stop key contacts SP, to line 72. Thus it is seen that when contacts 65 open after a predetermined number of cards 50 have been fed, the motor relay magnets MR are deenergized and their contacts MR-1, MR-2 open the motor circuit.

In Fig. 6, all the keys are unlocked and the machine may be run whether the counter is pre-set or not. Assuming that the counter is not pre-set, then the start circuit passes through contacts 51a rather than contacts 65. The motor circuit is the same, and the motor control circuit is the same except for contacts 51a being 60 in the circuit in place of contacts 65.

When all three keys are locked, as illustrated in Fig. 7, the machine cannot be run whether the counter is pre-set or not. Even if the counter is pre-set, as shown, no start circuit may be completed because contacts 49 are open. Thus, mag-

nets MR remain deenergized keeping the motor at rest.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine of the class described, a card holding magazine, a printing station, means for feeding cards successively from the magazine to and past the printing station, printing means at said station including a printing drum comprising a shiftable U-shaped member with a printing plate mounted thereon and a platen adjacent thereto in continuous rotation during operation of the feeding means for printing on predetermined portions of said cards, means normally biasing the printing plate away from the platen, means for shifting said printing plate toward the platen during each revolution of said drum, restraining means cooperating with the shifting means for overcoming the effect of the biasing means to keep the printing plate in an operative position, and card controlled means actuated in accordance with the passage of cards between the magazine and the printing station for controlling the releasing of the restraining means so as to determine whether the printing plate is to remain in printing engagement with the platen during each revolution of the drum.

2. A printing machine comprising a magazine for holding record cards, a printing station, means for feeding the cards one by one from the hopper to and past the printing station, printing means at said station including a printing drum comprising a shiftable U-shaped member with a printing plate thereon and a platen adjacent thereto, means connecting the printing means with the feeding means for rotating the drum and the platen in predetermined relationship with said feeding means so that printing may be effective on preselected portions of the cards, cam operated means for moving the U-shaped member to its printing position during each revolution of the drum, means normally biasing said member out of printing position, means for latching said member in its non-printing position so as to overcome the effect of the biasing means, and card controlled means actuated in accordance with the passage of cards between the hopper and the printing station for controlling the releasing of the member from the latching means so as to determine whether the printing plate is to remain in printing engagement with the platen during each revolution of the drum.

3. A printing machine comprising a card holding magazine, a printing station including a rotatable printing plate and a platen, means for feeding record cards one by one from the magazine to the printing station so as to cause said cards to pass between said plate and said platen, means for rotating the plate and the platen in fixed relation with the feeding means, card controlled means normally holding said printing plate away from said platen but actuated upon engagement with cards in their passage from the magazine to the printing station to cause said plate to be moved into printing engagement with

the platen to effect printing on predetermined portions of said cards, and pre-settable means controlling the feeding means as to the number of cards to be fed for rendering the card controlled means ineffective to cause printing movement of the printing plate after such number of cards has been fed thereby.

5. A printing machine comprising a record holding magazine, a printing station including a printing drum comprising a shiftable U-shaped member having a type carrier thereon and a platen adjacent thereto, means for feeding a record from the magazine to and past the printing station, means at the printing station for biasing the U-shaped member to an inoperative position, a record controlled lever intermediate the magazine and the printing station normally permitting said biasing means to be effective to hold the type carrier in a non-printing position, cam operated means for camming the type carrier into printing position during a feeding operation, latching means cooperating with the cam operated means to hold the type carrier in operative printing position with respect to the platen, 25 means normally effective upon completion of the printing operation for tripping the latching means to cause the type carrier to be biased to its non-printing position, and means controlled by the record control lever as long as records are 30 passing from the magazine to the printing station for rendering the tripping means ineffective.

6. A printing machine comprising a card holding magazine, a printing station including printing plate mounted on a shiftable support and a platen adjacent said plate, drive means for feeding record cards one by one from the magazine to the printing station and for rotating the print-

ing plate and platen in fixed relationship, a spring normally positioning said plate in a non-printing position, cam operated means effective during each revolution of the printing plate for shifting said plate to the printing position by 5 overcoming the action of the spring, a latch for holding the plate in said printing position, means normally effective for tripping the plate off the latch during the same revolution in which it is latched, a card controlled lever for rendering the 10 tripping means ineffective as long as cards are feeding, and presettable means for rendering the tripping means effective after a predetermined number of cards has been fed past the printing station so as to cause the plate to be returned 15 by the spring to its non-printing position.

7. In a printing machine including a printing plate and a platen and means for rotating said plate and platen to effect a rolling print on record material therebetween, inking means for said 20 plate including an inking roll and perforated tubing extending internally therein, means for supplying ink through the perforations in said tubing to said inking roll including means for imparting relative rotation between the roll and the tubing, 25 said roll contacting the printing plate during each revolution of the latter and prior to the printing operation to supply the ink for effecting the imprint on the record material, and said inking roll being readily removable from its operating position and being provided with a sealing washer, a receptacle being provided into which said roll may be placed when not in use adapted to be sealed by the washer upon insertion of the roll fully into said receptacle. 30

EUGENE A. FORD. 35
